GREEN & McFISHER.

Straw Cutter.

No. 22,072.

Patented Nov. 16, 1858.

UNITED STATES PATENT OFFICE.

WILSON GREEN AND MALCOM McFISHER, OF CHATTANOOGA, TENNESSEE.

STRAW-CUTTER.

Specification of Letters Patent No. 22,072, dated November 16, 1858.

To all whom it may concern:

Be it known that we, WILSON GREEN and MALCOM McFISHER, of the town of Chattanooga, Hamilton county, State of Tennessee, have invented a new and Improved Straw-Cutter; and we do hereby declare that the following is a full and exact description thereof, reference being had to the accompanying drawings and letters of reference 10 marked thereon, in which—

A represents the treadle or lever. B the knife. (a) the connection of the knife with the lever. C the double leafed wooden spring and (c) the connection of the lever 15 with the spring which elevates the knife.

D is a leather strap on the end of the treadle forming a stirrup in which the right foot is placed to assist the spring to raise the knife should it from any cause become 20 wedged between the jaws when the cut is made.

E is a lever worked with the right hand and serves to press the straw firmly into the box while being cut, causing the knife to 25 cut much easier.

F is an upright in which both levers work.

G is a board attached to the treadle moving up and down in front of the knife regulating the length of cutting the straw.

30 The entire machine is simple and easy of

construction and can be made at a small expense the whole being wood except the knife and jaws, which are of iron, the blade which is of steel is welded to the bars of iron at each end forming a right angle triangle. 35

This machine is worked in the following manner viz: The knife being raised by the spring, the straw is placed in the box and shoved forward with the left hand or rather under the lever worked with the right hand 40 until it comes in contact with the board G, when the foot is placed in the stirrup at the end of the treadle and the knife is brought down between the jaws, and raised again before the press is taken off the straw, then 45 the press is slightly raised, the straw shoved forward and the cut repeated, which may be done three of four times per second.

What we claim as our invention and desire to secure by Letters Patent is— 50

The arrangement of the treadle A, leather strap D, the regulating board C, and knife B, combined with the double leafed lever C, lever E, and upright standard F, for joint operation as set forth and described.

WILSON GREEN.

MALCOM McFISHER.
